(57) **CLAIM**

We claim the ornamental design for an automotive vehicle rear spoiler, as shown and described.

DESCRIPTION

FIG. 1 is a perspective view of an automotive vehicle rear spoiler, of the new design;

FIG. 2 is an enlarged perspective view thereof;

FIG. 3 is a top view thereof;

FIG. 4 is a rear view thereof;

FIG. 5 is a side view thereof;

FIG. 6 is a back view thereof, opposite that of FIG. 5;

FIG. 7 is a bottom view thereof; and,

FIG. 8 is a back view thereof.

The broken and dotted lines illustrate environment and portions of the automotive vehicle rear spoiler which form no part of the claimed design.

1 Claim, 7 Drawing Sheets
